INTEGRATED LOGIC CIRCUIT

This invention relates generally to integrated logic circuits, and more particularly to ratioless-type integrated logic circuits using two-phase clock pulses.

Metal insulator semiconductor (MIS) field effect transistors or metal oxide semiconductor (MOS) transistors have been recently employed in digital logic circuits for the following reasons.

Large-scale integrated circuits using the MOS transistors require relatively few diffusion processes in manufacture and hence are relatively easily fabricated with a low percentage of rejects due to manufacturing defects. Further, such integrated circuits have a relatively low power consumption. However, a logic circuit employing a conventional ratio-type MOS transistor requires many large-sized MIS transistors as loads and this imposes a limitation on the number of transistors that can be provided on a semiconductor substrate of a given size.

Although a conventional ratio-less type logic circuit permits the use of small MIS transistors so that relatively large numbers of the transistors can be provided on a substrate of a given size, this circuit also necessitates power source conductors for supplying power to the MIS transistors, grounding conductors and conductors for a three- or four-phase clock pulse, in addition to conductors connected with the input and output terminals. The electric fields of these conductors exert an influence upon the substrate, so that the transistors cannot be disposed as close to one another as would otherwise be expected and the overall power consumption cannot be reduced to the full extent made possible by the small MIS transistors.

Accordingly, it is an object of this invention to provide integrated circuits that are free of the above-mentioned disadvantages of previously proposed circuits using MOS or MIS transistors.

A specific object of the invention is to provide compact integrated logic circuits that do not require a DC power source.

Another object is to provide integrated logic circuits in which the semiconductor substrate common to all of the transistors functions as a grounding conductor.

A further object is to provide digital logic circuits employing relatively small numbers of transistors.

A still further object is to provide ratio-less type integrated circuits which are operated by the supplying of clock pulses thereto, and which do not require a DC power source.

Such ratio-less type integrated circuits according to the invention have the following advantages:

1. The clock pulse may be two-phase so that the wiring or conductors required for the integrated circuit are simplified.

2. Since the MIS transistors employed may be of the same miniaturized size, their density on a common substrate may be high and their switching speed is high.

3. Since the signal level is determined independently of the transconductance g_m of the MIS transistors, dispersion caused in the manufacture of the MIS transistors does not matter and this facilitates the fabrication of the integrated circuit. Further, the resulting integrated logic circuit is not adversely affected by noise.

4. A current flows in the circuit only when a clock pulse is supplied and it is sufficient only to charge the stray capacity of the MIS transistor circuits, so that power consumption is small.

5. Neither a DC power source nor interconnections for power source supply are required.

6. A grounding connection need not be provided on the upper surface of the integrated circuit and instead the substrate is utilized as a conductor to ground. Accordingly, an insulator for example of silicon dioxide or silicon nitride, can be formed thin on the integrated circuit, and hence production of the integrated circuit is facilitated.

7. Since the current of the clock pulse flows only when the stray capacity is charged, a clock pulse generator that is simple in construction may be employed as the source of the clock pulses.

The above and other objects, features and advantages of the invention, will be apparent in the following detailed description

of illustrative embodiments to be read in connection with the accompanying drawings, in which:

FIGS. 1, 3 and 5 are circuit diagrams of integrated logic circuits according to several embodiments of the invention;

FIGS. 2, 4 and 6 are waveform diagrams to which reference will be made in explaining the operation of the embodiments of FIGS. 1, 3 and 5, respectively; and

FIGS. 7A, 7B and 7C are circuit diagrams of several combinational circuits that can be employed in logic circuits embodying this invention.

Generally, in accordance with this invention, a circuit comprises two MIS transistors and having no power source terminal and a combinational circuit consisting of an AND gate circuit, an OR gate circuit, a bridge circuit or a combination thereof, also having no power source terminal and such components are formed as one unit on the same semiconductor substrate to provide an integrated logic circuit.

In FIG. 1 there is illustrated a delay multivibrator circuit having the foregoing general arrangement and in which the MIS transistors are N-type enhancement insulated gate field effect transistors. If the polarity of a voltage used is reversed, P-type insulated gate field effect transistors can be employed.

In FIG. 1, reference character A indicates a combinational circuit which is made up of a single MIS transistor M_1 , having neither a power source terminal nor an input terminal for clock pulse supply. The gate of MIS transistor M_1 is connected to an input terminal T_1 and the source of MIS transistor M_1 is connected to the gate and source of a MIS transistor M_2 , with the gate and source of MIS transistor M_2 being also connected to a first clock pulse input terminal t_1 . The drain of MIS transistor M_1 is connected to a junction X_1 , which is also connected to the drain of MIS transistor M_2 and the source of a MIS transistor M_3 . The gate of MIS transistor M_3 is connected to a second clock pulse input terminal t_2 . Thus, a circuit unit according to this invention is provided the output of which is derived from the drain of MIS transistor M_3 .

Further, in the embodiment of FIG. 1, the drain of MIS transistor M_3 is connected through a junction X_2 to the gate of a MIS transistor M_5 of a combinational circuit A' which has neither a power source terminal nor a clock pulse input terminal. The source of the MIS transistor M_5 is connected to the second clock pulse input terminal t_2 and to the gate and source of a MIS transistor M_6 . Further, the drain of MIS transistor M_5 is connected to a junction X_3 which is also connected to the drain of MIS transistor M_4 and the source of a MIS transistor M_4 . An output terminal T_2 is connected to the drain of MIS transistor M_4 and the gate of MIS transistor M_4 is connected to the first clock pulse input terminal t_1 . In this case, the MIS transistors M_1 to M_6 are formed on a common semiconductor substrate and means (not shown) connect the substrate to ground.

A clock pulse CP_1 , such as is shown in FIG. 2A, and another clock pulse CP_2 , such as is depicted in FIG. 2B, which has the same period as that of clock pulse CP_1 but a predetermined phase difference therefrom, are respectively applied between the terminals t_1 , t_2 and the substrate ground.

In the following description of the operation of the circuit shown in FIG. 1, it will be assumed that the input terminal T_1 is supplied with an input pulse S_1 , such as is depicted in FIG. 2C, which rises and falls in correspondence with the occurrence of pulses of the clock pulse CP_1 . Further, in the following description a positive logic is used and a higher level of two values will be referred to as a level "1" and a lower level as a level "0."

With the input pulse S_1 applied by way of terminal T_1 to the gate of transistor M_1 , the transistor M_1 is in the on state during each period when the input pulse S_1 is at the level "1" and is in the off state during each period of the level "0." Further, upon application of a clock pulse CP_1 to the gate of transistor M_2 , transistor M_2 is turned on in the duration of the pulse CP_1 and, since the pulse CP_1 is also applied to the source of transistor M_2 , the stray capacity, formed between the junction X_1 on the drain side of transistor M_2 and the substrate and the wiring for

the clock pulse are charged, whereby there is produced at the junction X_1 an output of the level "1" for the duration of the pulse CP_1 . When the pulse CP_1 decays, transistor M_2 is changed to its off state and if the transistor M_1 is then in the on state, the charge stored at the junction X_1 which is the output of the level "1" is discharged through transistor M_1 to provide an output of the level "0" at junction X_1 . If, at the time of the decay of pulse CP_1 , transistor M_1 is in the off state, the output of the level "1" at the junction X_1 is held unchanged. Consequently, an output S_2 , such as is depicted in FIG. 2D, is produced at junction X_1 in response to the input pulse S_1 at terminal T_1 .

With application of the clock pulse CP_2 to the gate of transistor M_3 , transistor M_3 is turned on for the duration of the pulse CP_2 during which the level at the junction X_1 is "0." Accordingly, if transistor M_1 is in the on state when the level at the junction X_2 of the drain side of the transistor M_3 is "1," the charge at junction X_2 is discharged through transistors M_1 and M_3 to lower the level at junction X_2 down to "0" and hold it unchanged. If the level at junction X_1 is "1," and consequently the transistor M_1 is held in the off state, the stray capacity at junction X_2 is charged by the charge at junction X_1 up to the level "1" and, when the clock pulse CP_2 has decayed to the level "0" to turn off transistor M_3 , the state at junction X_2 is memorized, so that there is produced at junction X_2 an output pulse S_3 , such as is shown in FIG. 2E in response to the output pulse S_2 at junction X_1 . It will be seen that the original S_3 is the inverse of the input original S_1 , and is delayed by one-half period behind the input signal S_1 . The foregoing represents the fundamental operation of a logic circuit unit according to this invention.

Further, in the circuit of FIG. 1, the output pulse S_3 is produced at the junction X_2 and is applied to the gate of transistor M_5 to hold it in the on state in the period of the level "1" of the pulse S_3 and hold it in the off state in the period of the level "0" of the pulse. While the clock pulse CP_2 is applied to the gate of the transistor M_6 to turn it on during the duration of the pulse CP_2 , the pulse CP_2 is also applied to the source of transistor M_6 to produce an output of the level "1" at junction X_3 at the drain side of transistor M_6 during duration of the pulse CP_2 . After the duration of the pulse CP_2 , the transistor M_6 is turned off and, if transistor M_5 is in the on state, the charge at junction X_3 , which is an output of the level "1," is discharged through transistor M_5 to produce an output of the level "0" at junction X_3 . If transistor M_5 is in the off state, the output of the level "1" at junction X_3 is held unchanged. Consequently, there is derived at junction X_3 an output pulse S_4 such as is depicted in FIG. 2F in response to the output pulse S_3 at junction X_2 .

Under such conditions, the pulse CP_1 is applied to the gate of transistor M_4 to turn it on for the duration of the pulse CP_1 and, if the level of the output pulse S_4 at junction X_3 is "1" while transistor M_4 is in the on state, an output of the level "1" is produced at the drain side of transistor M_4 and consequently at the output terminal T_2 . In the event that the level of the output pulse at junction X_3 is "0," an output of the level "0" is derived at the output terminal T_2 . Thus, there is produced at output terminal T_2 an output pulse S_5 , such as is shown in FIG. 2G in response to the output pulse S_4 at junction X_3 .

Accordingly, it will be apparent that application of the input pulse S_1 FIG. 2C to the input terminal T_1 results in the output pulse S_5 FIG. 2G being produced at the output terminal T_2 . A comparison of the input pulse S_1 and the output pulse S_5 shows that the output pulse S_5 is delayed behind the input pulse S_1 by one period of the clock pulse, that is, by one bit time. Thus the circuit described above with reference to FIG. 1 functions as a delay multivibrator.

It will be apparent from the foregoing that the MIS transistor M_1 to M_6 operate with the clock pulse as a power source and that the transistors are not otherwise supplied with power from any external source. Thus, there is no continuous DC current flow in the transistors M_1 to M_6 and, in addition, the current for the clock pulse supply is a mere charging cur-

rent for the small stray capacity. Therefore, the overall power consumption of the circuit is extremely low.

Further, since DC current is not supplied to the transistors M_1 to M_6 at all times, the usual power source of such DC current and power source the wiring or conductors therefor are unnecessary, which makes possible simplification of the overall construction, especially when the transistors M_1 to M_6 are formed on a common semiconductor substrate as previously described. Further, in circuits according to the invention the semiconductor substrate is grounded, so that individual conductors for grounding the semiconductor substrate for the respective transistors are unnecessary and this further simplifies the overall circuit construction.

Since transistors M_2 and M_6 are in the off state at the time when the levels of the outputs at junction X_2 and terminal T_2 are "0," the mutual conductance of transistors M_2 and M_6 need not to be so low as that required in the case where transistors M_2 and M_6 serve as loads in order to produce a step valve from the output level "0" to the output level "1" which is sufficiently high to cause the output level to be "0" at junction X_2 and terminal T_2 . Accordingly, transistors M_2 and M_6 need not be larger in size than transistors M_1 and M_3 , as distinguished from existing ratio-type logic circuits. Therefore, this invention makes possible the production of the integrated logic circuit on a semiconductor substrate of small area. On the other hand, if transistors M_2 and M_6 were made to be in the on state and a current could be applied to junctions X_1 and X_3 at the time when the output levels at junction X_2 and terminal T_2 are "0," the output level "0" could not be made to have a sufficiently great difference from the output level "1" unless the mutual conductance of transistors M_2 and M_6 was sufficiently decreased or that of transistors M_1 and M_3 was very substantially increased so as to provide the "0" output level at junction X_2 and the terminal T_2 . Further, since transistors M_2 and M_6 need not have a low mutual conductance, it is possible to substantially shorten the rising time of pulses S_2 and S_4 when transistors M_2 and M_6 are in the on state, thereby to raise the clock pulse frequency and allow high-speed operation of the integrated logic circuit. In addition, even if the pulse width of the clock pulse is widened, the current flow is only enough to charge a small stray capacity of the circuit and memorize it. Therefore, it is not necessary to use a clock pulse of small pulse width to maintain a low power consumption, as widening of the pulse width will not appreciably increase the power consumption.

In the foregoing, the period of the clock pulse CP_2 has been issued to be equal to that of the clock pulse CP_1 . However, even if a clock pulse CP_2' , such as is depicted in FIG. 2B', is employed which is synchronized with the pulse CP_2 of FIG. 2B, but is produced at intervals of a multiple of the period of the pulse CP_2 , the output pulses S_2 , S_3 and S_4 at junctions X_1 , X_2 and X_3 , respectively, become as shown in FIGS. 2D, 2E' and 2F' in response to the input pulse S_1 depicted in FIG. 2C, thus deriving at the output terminal T_2 an output pulse S_5 such as is shown in FIG. 2G'.

Turning now to FIG. 3, it will be seen that the present invention is there shown applied to another delay multivibrator circuit, in which elements corresponding to those in FIG. 1 are identified by the same reference numerals. In the circuit of FIG. 3 the drain of a MIS transistor M_7 is connected to the gate of MIS transistor M_1 , the gate of transistor M_7 is connected to the source of transistor M_1 and input terminal T_1 is connected to the source of transistor M_7 . In this case, MIS transistor M_1 again constitutes a combinational circuit A having neither a power source terminal nor an input terminal for clock pulse supply. The drains of MIS transistors M_1 and M_2 are interconnected and connected to the source of MIS transistor M_3 . The source of transistor M_1 and the source and gate of transistor M_2 are connected together and connected to the first clock pulse input terminal t_1 . The gate of transistor M_3 , the source of MIS transistor M_3 and the source and gate of MIS transistor M_6 are connected to the second clock pulse input terminal t_2 . Further, the drain of transistor M_3 is con-

nected to the gate of transistor M_5 and the drains of transistors M_3 and M_4 are interconnected and connected to the signal output terminal T_2 . In this case, the MIS transistors M_1 , M_2 , M_3 , M_5 , M_6 and M_7 are also formed on a common semiconductor substrate which is grounded.

The terminal t_1 is supplied with a clock pulse CP_1 such as is depicted in FIG. 4A and terminal t_2 is supplied with a clock pulse CP_2 such as is shown in FIG. 4B. The following description will assume that the signal input terminal T_1 is supplied with an input pulse S_1' such as is depicted in FIG. 4C and which again rises and falls in correspondence with pulses of the clock pulse CP_2 .

When the clock pulse CP_1 is applied to the gate of transistor M_7 to turn it on for the duration of the pulse CP_1 , and if the level of the signal S_1' fed to input terminal T_1 is "0," the output level at junction X_1' on the drain side of transistor M_7 becomes "0" and, if the level of signal S_1' is "1," the level of the output at junction X_1' becomes "1." Thereafter, when the level of the clock pulse CP_1 becomes "0" to turn off the transistor M_7 , the state of junction X_1' is memorized, so that an output pulse S_2' , such as is depicted in FIG. 4D is derived at junction X_1' in response to signal S_1' .

The pulse signal S_2' is applied to the gate of transistor M_1 , so that transistor M_1 is caused to be in the on state while pulse S_2' is at the level "1" and transistor M_1 is held in the off state while pulse S_2' is at the level "0." The clock pulse CP_1 is applied to the gate and source of transistor M_2 to turn it on, and the charge by the current of the clock pulse CP_1 produces at junction X_2' on the drain side of transistor M_2 an output whose level is "1" for the duration of the pulse CP_1 . When the pulse CP_1 decays, transistor M_2 is turned off, in which case, if transistor M_1 remains in the on state, the charge at the junction X_2' , where the output has been at the level "1," is discharged through transistor M_1 to produce an output of the level "0" at junction X_2' . In the event that transistor M_1 is in the off state where pulse CP_1 decays, the output of the level "1" at junction X_2' is held unchanged. Consequently, an output pulse S_3' such as is depicted in FIG. 4E is derived at junction X_2' in response to the signal S_2' .

Further, the clock pulse CP_2 is applied to the gate of transistor M_3 to hold it in the on state for the duration of the pulse CP_2 during which the output at junction X_2' is at the level "0." Consequently, in the event that transistor M_1 is in the on state when the output at junction X_3' on the drain side of transistor M_3 is at the level "1," the charge at junction X_3' is discharged through transistors M_1 and M_2 to lower the level of the signal at junction X_3' to "0." On the other hand, when the level of the signal at junction X_3' is "0," such signal remains unchanged. When the signal at junction X_2' is at the level "1," and hence transistor M_1 is in the off state, the signal at junction X_3' is charged up to the level "1" by the charge at junction X_2' and the level of the clock pulse CP_2 is lowered to "0" to turn off transistor M_3 and the state at junction X_3' is memorized. Consequently, an output pulse S_4' such as is shown in FIG. 4F is produced at junction X_3' in response to the output pulse S_3' .

The resulting output pulse S_4' is supplied to the gate of transistor M_5 , so that transistor M_5 is in the on state while pulse S_4' is at the level "1" and transistor M_5 is in the off state when the pulse S_4' is at the level "0." The clock pulse CP_2 is applied to the gate of transistor M_6 to turn it on and hold it in the on state for the duration of the pulse CP_2 , and, at the same time, the pulse CP_2 is fed to the source of transistor M_6 , by which an output of the level "1" for the duration of the pulse CP_2 is produced at a point on the drain side of the transistor M_6 , that is, at the output terminal T_2 , by the current of the clock pulse CP_2 flowing in transistor M_6 . Upon the decay of the pulse CP_2 , transistor M_6 is turned off and, if transistor M_5 is then in the on state, the charge at terminal T_2 which has been an output of the level "1" is discharged through transistor M_5 , producing an output of the level "0" at terminal T_2 . If transistor M_5 is in the off state upon the decay of pulse CP_2 , the output at output terminal T_2 is held unchanged at the level

"1." As a result of this, an output pulse S_5' such as is shown in FIG. 4G is produced at the terminal T_2 in response to the output pulse S_4' at junction X_3' .

Thus, when the input pulse S_1' shown in FIG. 4C is applied to input terminal T_1 , the output pulse S_5' depicted in FIG. 4G is produced at the output terminal T_2 , and it will be seen that output pulse S_5' is similar to the input pulse S_1' , but delayed with respect to the latter by one bit time. Accordingly, the circuit as illustrated in FIG. 3 also performs the function of a delay multivibrator circuit.

Further, it will be understood that the same operational effects as those previously described with reference to FIG. 1 can be obtained with the construction of FIG. 3.

The foregoing description of operation has assumed that the period of the clock pulse CP_1 is equal to that of the clock pulse CP_2 . However, even if a clock pulse CP_1' , such as is shown in FIG. 4A', is employed which is synchronized with the pulse CP_1 of FIG. 4A but produced at intervals of a multiple of the period of the pulse CP_1 , the output pulses S_2' , S_3' and S_4' at the junctions X_1' , X_2' and X_3' , respectively, are then illustrated in FIGS. 4D', 4E' and 4F' as a result of the input pulse S_1' shown in FIG. 4C, thus producing at the output terminal T_2 an output pulse S_5' as depicted in FIG. 4G'.

Referring now to FIG. 5, it will be seen that the present invention is then shown applied to a set-biased multivibrator circuit, in which the MIS transistors are P-type enhancement insulated gate field effect transistors and elements similar to those of FIG. 1 are identified by the similar reference numerals. In the circuit of FIG. 5, a reset signal input terminal R is connected to the gate of a MIS transistor M_1 constituting a combinational circuit A having neither a power source terminal nor a clock pulse input terminal, and the source of transistor M_1 is connected to the gate and source of a MIS transistor M_2 . The gate and source of transistor M_2 are interconnected and the connection therebetween is connected to a first clock pulse input terminal t_1 . The drain of transistor M_1 is connected at a junction Y_1 with the drain of transistor M_2 and with the source of a MIS transistor M_4 . The gate of transistor M_3 is connected to a second clock pulse input terminal t_2 . The drain of transistor M_3 is connected at a junction Y_2 to the gate of a MIS transistor M_8 . The source of transistor M_8 is connected to the drain of a MIS transistor M_9 , which in turn, has its source connected to the second clock pulse input terminal t_2 . Further, the drain of the transistor M_8 is connected, at a junction Y_3 , with the source of a MIS transistor M_{10} and with the drain of a MIS transistor M_{11} . The gate and source of transistor M_{11} are connected to the second clock pulse input terminal t_2 . A connection point between the drains of transistors M_8 and M_{11} is connected to the drain of a MIS transistor M_{12} , and the source of the latter is connected to the second clock pulse input terminal t_2 while the gate of transistor M_{12} is connected to a set signal input terminal S . The gate of transistor M_{10} is connected to the first clock pulse input terminal t_1 and the drain of transistor M_{10} is connected to the gate of a MIS transistor M_{13} . The drain of transistor M_{13} is connected, at a junction Y_5 , with the drain of a MIS transistor M_{14} and with the source of a MIS transistor M_{15} . The source of transistor M_{13} and the gate and source of transistor M_{14} are all connected to the first clock pulse input terminal t_1 . The gate of transistor M_{15} is connected to the second clock pulse input terminal t_2 and its drain is connected to an output terminal T_2 and to the gate of transistor M_9 . Also in this case, the MIS transistors M_1 to M_3 and M_8 to M_{15} are formed on a common semiconductor substrate, which is grounded. It will be seen that a circuit A constituted by transistor M_1 , a circuit A' made up of the interconnected MIS transistors M_8 , M_9 and M_{12} are a circuit A'' constituted by the MIS transistor M_{13} are combinational circuits which have neither power source terminals nor clock pulse input terminals.

A clock pulse CP_1 , such as is shown in FIG. 6A, is applied to the first clock pulse input terminal t_1 and a clock pulse CP_2 , such as is depicted in FIG. 6B, is fed to the second clock pulse input terminal t_2 . The embodiment of FIG. 5 has been

described as employing P-type enhancement insulated gate field effect transistors as the MIS transistors. However, if the polarity of the voltage of the clock pulse used is reversed, N-type insulated gate field effect transistors can be employed.

In the following description of the operation of the circuit in FIG. 5, a negative logic is used and a higher level of two values will be referred to as a level "0" and a lower level as a level "1." Further, it will be assumed that the reset signal input terminal R is supplied with a reset input pulse R_0 such as is shown in FIG. 6C and which falls in synchronization with clock pulse CP_1 and that the set signal input terminal S is supplied with a set input pulse S_0 such as is depicted in FIG. 6D and which falls in synchronization with clock pulse CP_2 .

The reset pulse R_0 is applied to the gate of transistor M_1 so that transistor M_1 is held in the on state while the reset pulse R_0 is at the level "1" and the transistor is in the off state while the pulse R_0 is at the level "0."

The clock pulse CP_1 is fed to the gate of transistor M_2 so that transistor M_2 is held in the on state for the duration of the clock pulse CP_1 and, at the same time, the pulse CP_1 is applied to the source of transistor M_2 , whereby an output of the level "1" is produced for the duration of the pulse CP_1 at junction Y_1 on the drain side of the transistor M_2 by the current of the clock pulse CP_1 flowing through transistor M_2 . When the pulse CP_1 decays to turn off transistor M_2 and, at such time, transistor M_1 is in the on state, the charge at junction Y_1 where the output has been at the level "1" is discharged through transistor M_1 to lower the output at junction Y_1 down to the level "0." In the event that the transistor M_1 is in the off state when pulse CP_1 decays, the output at junction Y_1 remains at the level "1." Consequently, a pulse R_{01} such as is shown in FIG. 6E is derived at junction Y_1 in response to the reset pulse R_0 at the terminal R.

The application of the second clock pulse CP_2 to the gate of the transistor M_2 holds the latter in its conductive state for the duration of the pulse CP_1 during which the output level at junction Y_2 remains "0." Accordingly, when the transistor M_1 is in the on state, the charge of the output of the level "1" at junction Y_2 on the drain side of transistor M_3 is discharged through transistors M_1 and M_2 to lower the output level at junction Y_2 down to "0." When the output level at junction Y_2 is "0," it remains unchanged. When the output level at junction Y_1 is "1" and consequently transistor M_1 is in the off state, the output level at junction Y_2 is charged up to "1" by the charge at junction Y_1 and, when the clock pulse CP_1 is turned off to change transistor M_3 to its off state, the state at junction Y_2 is memorized. Thus, a pulse R_{02} such as is depicted in FIG. 6F is produced at junction Y_2 in response to the pulse R_0 at junction Y_1 .

Further, the set pulse S_0 is fed to the gate of transistor M_{12} so that transistor M_{12} is held conductive when the set pulse S_0 is at the level "1" and the transistor M_{12} is held nonconductive when the set pulse S_0 is at the level "0." The clock pulse CP_2 is applied to the gate of transistor M_{11} so that transistor M_{11} is held in the on state while the clock pulse CP_2 is "on" and, at the same time, the pulse CP_2 is applied to the source of transistor M_{11} , so that an output of the level "1" and a duration corresponding to the pulse duration of the pulse CP_2 is produced at junction Y_3 on the drain side of transistor M_{11} by the current of the pulse CP_2 flowing therethrough. When the clock pulse CP_2 decays, transistor M_{11} is turned off, in which case, if the transistor M_{12} is conductive, the charge at junction Y_3 is discharged through transistor M_{12} , producing an output of the level "0" at junction Y_3 . The output at junction Y_3 is affected by that at junction Y_2 . Thus, when the output of the level "1" is produced at junction Y_2 to turn on transistor M_8 and the output of the level "1" is derived at the output terminal T_2 to render transistor M_9 conductive, the charge at junction Y_3 is discharged through transistors M_8 and M_9 to provide an output of the level "0" at Junction Y_3 . In the cases where either of transistors M_8 and M_9 , or both of them are in the off state and transistor M_{12} is in the off state, the output of the level "1" at junction Y_3 is held unchanged. As a result of

this, a pulse S_{01} such as is depicted in FIG. 6G is derived at junction Y_3 in response to the set pulse S_0 at the terminal S, the pulse R_{02} at junction Y_2 and the signal at the output terminal T_2 .

- 5 The first clock pulse CP_1 is applied to the gate of transistor M_{10} , so that transistor M_{10} is held conductive while the clock pulse CP_1 is "on." In such a case, when the output level at the point Y_3 is "0," that is, transistor M_{12} is in the on state or the transistors M_8 and M_9 are both in the on state and the output level at junction Y_4 on the drain side of transistor M_{10} is "1," the charge at junction Y_4 is discharged through transistors M_{12} and M_{10} or through transistors M_8 , M_9 and M_{10} to lower the output level at junction Y_4 down to "0." When the output level at junction Y_4 is "0" it remains unchanged. In the event that the output level at junction Y_3 is "1," the output level at junction Y_4 is raised up to "1" by the charge at junction Y_3 and, when the level of the clock pulse CP_1 becomes "0" to turn off the transistor M_{10} , the state at junction Y_4 is 10 memorized. As a result of this, a pulse S_{02} such as is shown in FIG. 6H is produced at junction Y_4 in response to the pulse S_{01} at junction Y_3 .
- 15 The pulse S_{02} thus produced at junction Y_4 is applied to the gate of transistor M_{13} , by which the transistor M_{13} is held conductive while the pulse S_{02} remains at the level "1" and transistor M_{13} is rendered nonconductive while the pulse S_{02} is at the level "0." The clock pulse CP_1 is applied to the gate of transistor M_{14} to render transistor M_{14} conductive for the pulse duration of the pulse CP_1 and, at the same time, the pulse CP_1 is fed to the source of transistor M_{14} , through which the current of the pulse CP_1 flows to produce at junction Y_5 on the drain side of transistor M_{14} an output of the level "1" for the pulse duration of the pulse CP_1 . When the pulse CP_1 decays, transistor M_{14} is turned off, in which case, if transistor M_{13} is in the on state, the charge at junction Y_5 is discharged through transistor M_{13} to produce an output of the level "0" at junction Y_5 , whereas, if transistor M_{13} is in the off state, the output of the level "1" at junction Y_5 is held unchanged. Accordingly, a pulse S_{03} such as is depicted in FIG. 6I is produced at junction Y_5 in response to the pulse S_{02} at junction Y_4 .
- 20 The pulse CP_2 is supplied to the gate of transistor M_{15} so that the transistor M_{15} is held conductive or in its on state for the pulse duration of the pulse CP_2 . While transistor M_{15} is in the on state, if the level of the output pulse as junction Y_5 is "1," the output of the level "1" is derived at the drain side of transistor M_{15} and consequently at output terminal T_2 , whereas, if the level of the output at junction Y_5 is "0," the output of the level "0" is produced at the output terminal T_2 . Consequently, an output pulse S_{04} such as is depicted in FIG. 6J is derived at the output terminal T_2 in response to the output pulse S_{03} at junction Y_5 .
- 25 Thus, when the set signal S_0 is applied to the set signal input terminal S earlier than reset signal R_0 , the multivibrator circuit naturally initiates its operation with the set signal S_0 . However, if the reset signal R_0 is applied to the reset signal input terminal R earlier than the set signal S_0 by $\frac{1}{2}$ bit time, the signal S_{04} shown in FIG. 6J is produced at the output terminal T_2 . It will also be apparent that the same operational effects as those described with reference to FIG. 1 can be obtained with the set biased multivibrator circuit illustrated in FIG. 5.
- 30 The combinational circuits A, A', A'' and A''', which are made up of MIS transistors without any power source terminal and without any input terminal for the clock pulse supply, may be replaced by an OR circuit consisting of a plurality of MIS transistors connected in parallel relation as shown in FIG. 7A, or by an AND circuit consisting of a plurality of MIS transistors connected in series as shown in FIG. 7B, or by a bridge circuit consisting of MIS transistors as depicted in FIG. 7C. Further, it is also possible to use combinational circuits made up of the circuits of FIGS. 7A, 7B and 7C in combination. In FIGS. 7A, 7B and 7C, reference characters I_1 to I_5 indicate signal input terminals and t_0 and t_0' designate detected output terminals.

Further, it is preferred that capacitors C, C', C'' and C''' be connected between the gates and sources of MIS transistors M₃, M₄, M₇, M₁₀ and M₁₅ as indicated in broken lines on FIGS. 1, 3 and 5. With the provision of the capacitors, the sources sides of MIS transistors M₃, M₄, M₇, M₁₀ and M₁₅ are capacitively excited by the clock pulse so that, when the combinational circuits A, A', A'' and A''' are in the off state or the signal level at the input terminal T₁ in FIG. 3 is "1," the level "1" of the outputs on the source sides of MIS transistors M₃, M₄, M₇, M₁₀ and M₁₅ is increased more than in the corresponding embodiments as originally described and the outputs are derived at the output sides as charging voltages at the drain sides of transistors M₃, M₄, M₇, M₁₀ and M₁₅.

In any of the circuits described with reference to FIGS. 1, 3, and 5, the source and drain of each MIS transistor can be exchanged without altering the previously described operational effects.

Although several logic circuits embodying this invention have been described in detail herein with reference to the accompanying drawings, it is to be understood that the invention is not limited to these precise embodiments, and that various modifications and changes may be effected therein by one skilled in the art without departing from the scope or spirit of the invention.

What we claim is:

1. An integrated logic circuit for delaying an input signal by one bit period and having only two clock pulse receiving terminals, said integrated circuit comprising a first combinational circuit having an input terminal for receiving an input signal and two output terminals and consisting of at least one first field effect transistor, two additional first field effect transistors, a second combinational circuit having an input terminal and two output terminals and consisting of at least one second field effect transistor, two additional second field effect transistors, all of said transistors having a common substrate which is grounded, each of said transistors having a gate electrode, a source electrode and a drain electrode, means connecting in parallel relation the source-drain circuit of each of said first and second field effect transistors with said two output terminals of the respective combinational circuit, 40

40

means connecting the gate electrode of one of said additional first and second field effect transistors with one of said output terminals of said first and second combinational circuits, respectively, means connecting the source-drain circuit of the other of said additional first and second field effect transistors with the other of the output terminals of said first and second combinational circuits, respectively, means connecting said source-drain circuit of said other additional first field effect transistor with said input terminal of the second combinational circuit, means for supplying a first clock pulse to the gate electrodes of said one additional first field effect transistor and said other additional second field effect transistor by way of one of said two clock pulse receiving terminals, and means for supplying a second clock pulse to the gate electrodes of said other additional first field effect transistor and said one additional second field effect transistor by way of the other of said two clock pulse-receiving terminals, said second clock pulse avoiding overlapping with said first clock pulse, whereby said input signal delayed by one bit

15 period is obtained through the source-drain circuit of said other additional second field effect transistor.

2. An integrated logic circuit according to claim 1, in which said first and second clock pulses are timed to render said additional first field effect transistors and said additional second field effect transistors alternately conductive.

3. An integrated logic circuit according to claim 1, in which a capacitor is connected between said other output terminal of each of said combinational circuits and said gate electrode of said other additional first and second field effect transistors, respectively.

4. An integrated logic circuit according to claim 1, wherein at least one of said combinational circuits is in the configuration of an AND gate circuit.

5. An integrated logic circuit according to claim 1, wherein at least one of said combinational circuits is in the configuration of an OR gate circuit.

6. An integrated logic circuit according to claim 1, wherein at least one of said combinational circuits is in the configuration of a bridge circuit.
